BOX-ENDING MACHINE

William Richard Watson, East Walpole, Mass., assignor to Bird & Son, Inc., East Walpole, Mass., a corporation of Massachusetts

Application June 17, 1949, Serial No. 99,810

6 Claims. (Cl. 93—36.3)

The present invention relates to box making machines, and more particularly to box-ending machines by which the ends of a partially formed box may rapidly and effectively be secured.

While box-making apparatus of the type wherein an operator presents a partially formed box to a press-type machine for completion of the box end has long been employed, such apparatus has generally been relatively massive and cumbersome. On the one hand, it is necessary, for proper sealing of the box end, to apply heavy pressure to the box end formation, customarily of the order of several tons, if the sealing and setting of the adhesive is to be effected in a brief interval. On the other hand, if the machine is to be capable of a high rate of production, the pressing operation must be so controlled that it may be initiated with extreme rapidity and with a minimum of effort on the part of the operator.

Heretofore, such machines have been of the mechanical type, in which the pressing force is developed by massive cam and lever means or equivalent mechanism, with some form of one-revolution clutch mechanism for connecting the cam to its driving means for a single revolution, when the press is to be actuated. Because of the inertia of the heavy parts, and time lags in the control mechanism, the interval during which effective sealing pressure is applied to the box end is generally but a small part of the total time for one complete cycle of the machine.

With a view, therefore, to improving the general construction and mode of operation of machines of the aforesaid type, the present invention has as an object the provision of a machine that is capable of extremely rapid operation, yet provides a relatively long dwell in closed position, whereby heavy pressure is applied to the box end throughout a substantial portion of the machine cycle. As a result, the box may effectively be sealed with a minimum amount of adhesive, and it becomes possible to make effective use of the somewhat slower setting cold adhesives.

Another object of the invention is to provide a box-ending machine of extremely simple construction and operation, which will be capable of operation over long periods of time with a minimum of servicing and attention.

A further object of the invention is to provide a novel and improved form of control, which will prevent the operation of the machine during the initial phases of box presentation and insertion, but will, after the box is properly inserted, permit the operator to actuate the press and cause sealing pressure to be applied throughout a predetermined period of adjustable duration.

In accordance with these and other objects, the invention contemplates a machine wherein the sealing pressure is applied to the box end formation by electromagnetic means, so as substantially to eliminate heavy rotating parts, clutch mechanisms and the like.

The invention likewise contemplates as a feature thereof control means lying in the path of and encountered

by the box as the box is being advanced to the press, said control means being so arranged that the press is locked out of operation at this stage, the control being operative, however, after completion of insertion of the box end between the pressing surfaces to enable the press operation to be started by the operator immediately upon proper placement of the box within the press.

The several features of the invention will be more fully set forth in the following description, taken in conjunction with the accompanying drawings, wherein Fig. 1 is a view in left side elevation of a setting-up machine of the electromagnetically powered type; Fig. 2 is an oblique view looking from the right front, of the head portion of the machine; Fig. 3 is a view of a partially folded box blank of the type which the machine of the present invention is particularly adapted to complete; Figs. 4, 5 and 6 are left side views taken adjacent the pressing surfaces of the machine, showing the successive steps in presenting and inserting a partially formed box blank for completion and sealing of the end formation and particularly illustrating the operation of the presser bar by which the machine is set in operation; Fig. 7 is a sectional detail in front elevation of the lower pressing surface or former block and its support, taken on the line 7—7 of Fig. 4; Fig. 8 is a left side sectional detail thereof, taken on the line 8—8 of Fig. 7, likewise indicating details of the presser bar control mechanism; Fig. 9 is a detail view in front elevation of the clamp block for the presser bar and Fig. 10 is a schematic wiring diagram of the power and control circuits for the press.

Introductory background

The machine to be described is arranged for operation in the same general manner, and on much the same type of box blanks, as the machine illustrated in U. S. Patent No. 710,930 to G. R. Wyman. According to this extensively employed method of box making, a flat box blank is by successive steps partly folded, coated with adhesive in selected regions, further folded and finally subjected to sealing pressure, in a rapidly conducted sequence of operations. Certain of these operations are effected by manipulation of the box blank by the operator, with other operations carried out with the aid of power-actuated instrumentalities.

Thus, the machine shown in Fig. 1 is adapted to receive between its pressing surfaces 12 and 14 the end formation of the partially completed box blank shown in Fig. 3. This end formation comprises the infolded corner laps 16 of the side walls 18, and the adhesively coated end wing 20 and end wing extension 22. Just prior to insertion of the box end between the pressing surfaces, the end wing extension 22 is folded over the in-turned corner laps into the interior of the box, and the sealing pressure then applied. The operation is then repeated on the other end of the box.

General description of machine

The box-ending press of the invention is advantageously constructed, and is herein illustrated, as a separate instrumentality, mounted on its own pedestal or base separate from the adhesive-applying apparatus. However, the press section will generally be disposed in close relation to the adhesive-applying section, so that the operator may readily transfer the partially folded box blank, with adhesively coated end wing and extension, from the adhesive section to the press. Since the adhesive applying apparatus may advantageously be generally similar in construction and mode of operation to the adhesive-applying mechanism shown in the above mentioned Wyman patent, it is not herein illustrated and described.

The press indicated generally in Fig. 1 comprises a head section carried by a sleeve 30 that telescopes over the

rearwardly inclined portion 32 of a pedestal 34 secured to base 36. A bolt 38 serves to position the head section at a convenient height for the individual operator.

To support the lower pressing surface or former block 14, the sleeve 30 is provided with brackets 42 to which is secured a plate 44. The former block 14 and an intermediate spacer block 46 are mounted on the plate 44 by means of a bolt 48, the head of which projects below the plate and brackets in order to be readily accessible. In accordance with usual practice, the former block is changed when boxes of different sizes are to be set up. In order that the various sizes of former blocks may each be properly centered under the upper pressing surface, the plate 44 is provided with a slot 50 extending inwardly from the forward edge of the plate. Pins 52 register with bores in the under side of the former block to locate the latter on the spacer block 46 with the front edge of the former block aligned with a wiper plate 54 secured to and extending downwardly from the spacer block.

The upper or movable pressing member 12 is mounted at the lower end of a rod 56 extending downwardly from the power unit. A ball and socket connection 58 (see Fig. 4) permits limited universal tilting movement of the member 12 to insure uniform sealing pressure over the box end. A rubber bushing 60 serves to hold the member 12 substantially normal to the rod 56 when the press is open, while relative rotation of the member 12 is prevented by a rearward extension 62 that slidingly engages a rib 64 on the forward side of the sleeve 30.

The power unit, indicated generally at 68, by which the press is actuated, is advantageously of the electromagnetic type, although it will be understood that other types of power mechanism may be employed to effect the reciprocation of the rod 54 and pressure plate 12. The power unit is secured to a rigid bracket 70 at the top of the sleeve 30. Referring to Fig. 1, the cover 72 of the unit has been partially broken away to show an electromagnet 74, the configuration of which is that of an Σ of revolution about the center leg 76, and with windings 78 around said leg. The rod 56 passes upwardly through the center of the magnet, and carries at its top a soft iron disc 80 which bridges the poles of the magnet to complete the flux path. Preferably both the disc and the electromagnet are slotted radially at intervals to diminish eddy-current losses. A thin disc 82 of brass or other non-magnetic material is preferably employed between the disc and the poles of the electromagnet to prevent the parts coming into direct contact, with the possibility of "sticking" due to residual magnetism, in case the press is actuated without a box end between the pressing surfaces. A spacer 84 of rubber or other resilient material surrounds the rod 56 below the bracket 70 to check the rebound upon release of the press.

Control mechanism

The application of power to the electromagnet to energize the same and cause the press to close is effected by the operator upon completing the insertion of the box end between the pressing surfaces. Control is effected by means of a switch 90 of the type which is actuatable upon relatively small movement of the plunger 92. The switch is mounted on a bracket 94 at the side of the sleeve 30 and is operated by connections extending from a presser bar 96 located at the forward edge of the spacer block 46 between the top of the wiper plate and the edge of the former block.

The presser bar 96 is in the form of a rod extending laterally across the central portion of the front of the spacer block 46, and is carried by a pair of rods or arms 98 extending rearwardly through slots 100 in the spacer block. At the rear of the spacer block, the rods pass through a transverse presser bar clamp 102 having at one end a flat-headed screw 104 aligned with the plunger 92 of the switch 90. At its other end the clamp 102 is pro-

vided with a thumb screw 108 for securing the arms of the presser bar in adjusted position. In order that both arms may be clamped, a rod 110 (see Fig. 9) extends between the arms in a passage in the member 102 so that clamping pressure applied to one arm serves also to clamp the other arm. To permit adjustment of the presser bar 96 over a wide range of former block sizes, the rods 98 preferably extend through the sleeve 30 and project at the rear thereof.

The presser bar 96 is adjusted relative to the clamp 102 so that with the switch open the bar projects outwardly beyond the plane of the wiper plate a distance corresponding approximately to the range of movement required for actuating the switch. Thus, when the bar is pressed to a position substantially flush with the wiper plate, the switch is closed and the press actuated, by means to be described. To permit the bar to move rearwardly to such flush position, the edge of the spacer block is recessed at 114 to provide the necessary clearance.

Since the presser bar lies in the path of the box as the end wing and end wing extension are being wiped-up the plate preparatory to insertion of the box end between the pressing surfaces, it is necessary to prevent operation of the press during this engagement of the advancing box with the presser bar. This is accomplished by locking the presser bar out of operation upon engagement with the box end, and thereafter releasing the bar from inoperative condition to permit actuation by the operator after the box has been fully and properly inserted in the press.

To accomplish this automatic lock-out operation during advance of the box, the edge of the spacer block is provided, above the recess 114, with a ledge or shoulder 116 disposed rearwardly of the plane of the wiper plate a distance slightly less than the diameter or thickness of the presser bar 96. Thus, when the presser bar is set in normal fashion so as to project slightly beyond the wiper plate, the rear of the bar is substantially in alignment with the ledge, and will just clear the latter if the bar is lifted while in forward or released position.

As a result of this arrangement, when the presser bar is engaged by the box end during the wiping up of the end wing (see Fig. 4) the bar is raised to its upper position, in which it is backed up by the ledge 116. In this position, it is locked in forward position, and even though inward pressure be applied, it cannot move rearwardly to release the switch, and the press thus remains inactive. However, as soon as the end wing and its extension have gone by, the presser bar drops down by gravity to its normal position in alignment with the recess 114, permitting a range of rearward movement that will result in actuating the switch when the bar is pressed inwardly.

Power supply and control circuits

To energize the electromagnet and cause the press to close when the presser bar is moved inwardly, the magnet winding is supplied with current from power supply means indicated generally at 120 and conveniently mounted at the base of the machine. The power supply also includes suitable timing and control circuits to insure a predetermined dwell on "hold" when the press is actuated, and for readying the press for another operation as soon as one cycle has been completed.

Referring to the schematic wiring diagram, Fig. 10, direct current for energizing the magnet is provided by a rectifier 124, connected to the magnet by a solenoid-actuated switch 126, preferably of the mercury type. The switch is shunted by a resistor 128 and capacitor 130 to minimize arcing on switch-opening.

The power rectifier 124 is connected to the usual A. C. power line through a relay 136 the solenoid of which is energized, when the press is to be actuated, by direct current derived from rectifier 138 in series with dropping resistor 140. The circuit likewise includes a shunt capacitor 142 and bleeder resistor 144.

In the operation of the control circuit for the relay 136, the closing of switch 90 by actuation of the presser bar 96 serves to connect the solenoid of relay 136 through a series capacitor 146 to the control circuit supply. The initial surge of current in charging condenser 146 actuates the relay 136 and thereby connects the power rectifier 124 to line, causing solenoid 126 to be energized and connecting the magnet 68 to the power rectifier. As condenser 146 becomes charged, the current drops to a low value, insufficient to maintain relay 136 closed. As a result, even though switch 90 be held closed, the relay 136 will automatically open after a predetermined period, thereby disconnecting the power rectifier from the line and de-energizing the magnet. A variable resistor 148 in shunt with the solenoid of relay 136 permits adjustment of the flow of charging current to vary the duration of the period the relay remains closed, and hence the "dwell" of the press.

To insure that the press, when actuated, will remain closed for the full predetermined period, whether or not the switch 90 is held closed by the operator, a second plunger-actuated switch 150 is provided. This switch is mounted at the side of the sleeve 30 below the power head so as to respond to movement of the upper or movable presser plate 12. In order to be out of the way, the switch is conveniently arranged to be actuated by the rearward extension 62, acting on the switch plunger.

The switch 150 is of the double throw type, and is connected as shown in Fig. 10 so that when the press is in "down" or closed position, the series circuit through the condenser 146 and relay 136 is completed in the same manner as when switch 90 is closed. Accordingly, even though the operator allows switch 90 to open by releasing the presser bar 96 before the pressing and sealing operation is fully completed, it will have no effect on the duration of the press "dwell," because of the parallel circuit provided by switch 150.

As soon as the charging of condenser 146 is completed, however, the press will open due to the de-energization of relay 136 as already indicated. The other pair of contacts of switch 150 will thereupon be closed, disconnecting the condenser 146 from the charging circuit and connecting a bleeder resistor 152 across the condenser terminals to dissipate rapidly the charge and ready the condenser for a new cycle.

By the above described arrangement, it will be seen that the actuation of the press requires only a brief pressure on the presser bar 96 to bring about the closing of the press, and that the duration or dwell of the pressing period is automatically determined, independently of whether the operator holds the presser bar closed for the full time or only for a brief interval thereof.

Operation

The operation of the machine follows in many respects that of the Wyman Patent No. 710,930. The operator picks up a flat blank from a stack and folds down the side walls 18 and inturns the corner laps 16 at one end. The end wing and end wing extension are then coated with an adhesive, advantageously in the same manner and with much the same type of gluing mechanism as shown in said Wyman patent.

The box is now transferred to the press section, the end wing and its extension being brought into contact with the wiper plate 54 as the box is tilted to an approximately vertical position with the end to be sealed at the top. The box end is then "wiped up" the plate 54, and during this upward advance the end wing extension engages the presser bar 96 to lift the same to its displaced position in which it is opposite the ledge or abutment 116, thus rendering it incapable of inward movement to actuate the press. Since the presser bar extends but slightly beyond the plane of the wiper plate, the box end readily is carried past the presser bar to a position in which the

box end is opposite the opening between the pressing members. The forward overhang of the upper pressing member 12 serves to stop the upward movement of the box opposite the opening. In the meantime the presser bar, freed of the box end, drops by gravity to its normal position in which rearward clearance is available for inward movement of the bar.

As soon as the box reaches the limit of its upward movement, the operator pushes the box end into the space between upper and lower pressing surfaces, thereby causing the end wing extension to be wiped around the corner laps and into the box. When the box has been fully inserted, the parts appear substantially as shown in Figure 5. Due to the tendency of the box bottom to bow outwardly, it will be seen that the box end may be fully inserted before the box bottom comes into full contact with the wiper plate. As a consequence, the operator must exert pressure on the box bottom in the general region opposite the presser bar in order to move the presser bar inwardly and actuate switch 90. By such arrangement, it is required that the box end will be fully and completely inserted in the press before the press is actuated, so that sealing pressure may be applied over the entire area to be glued, thus insuring high and uniform quality of production. This mode of actuation of the press is to be distinguished from treadle-actuated and other arrangements wherein an operator may bring about press closing before a box has been fully inserted, thus producing boxes of inferior quality because of incomplete sealing.

As soon as the operator has pressed the box bottom to close switch 90 and energize the electromagnet, the operator may release the actuating pressure on the box bottom, and may even start to pull the box from the machine, without interfering with the dwell of the press. This result occurs by reason of the supplementary switch 150 which takes over control of the holding and de-energizing circuits once a pressing operation has been initiated by the operator. The box may therefore be quickly withdrawn from the machine as soon as the press starts to open, thus contributing to the speed of operation.

It will therefore be apparent that there has been provided a press in which the insertion of a box, actuation of the press, and removal of the box, may be carried out with ease and speed, so that the operator may achieve a high rate of production. At the same time, due to the rapid response of the control mechanism, a dwell or sealing period of appreciable duration may be provided within a relatively short over-all cycle, so as to permit effective sealing and setting of the box end even with the somewhat slowly setting cold adhesives. In addition, an advantage of major importance is the arrangement which insures that the box end must be fully and completely inserted before the press can be closed.

While the invention has been described and illustrated in terms of a preferred embodiment thereof, it will be understood that the invention is not so limited, but comprehends other constructions and arrangements within the scope of the appended claims.

I claim as my invention:

1. A box making machine for securing the ends of a partially formed box, said machine comprising relatively movable pressing members between which adhesively-coated and inwardly folded portions of a box end are adapted to be inserted, power operated means for effecting movement of one of said pressing members relative to the other, a wiper plate in contact with which the box end is advanced toward the pressing members and over which the box fits when the box end is inserted between the pressing members, a presser bar disposed substantially in the plane of the wiper plate and in the path of and engaged by the box end during the advance of the box along the plate to the pressing members said presser bar being mounted for movement inwardly of the plane of the wiper plate to effect actuation of the power-oper-

ated means, and means operative independently of the force of engagement of the box end on the wiper plate during box advance for positively preventing inward movement of the presser bar during advance of the box end to the pressing members.

2. A box making machine for securing the ends of a partially formed box, said machine comprising relatively movable pressing members between which adhesively-coated and inwardly folded portions of a box end are adapted to be inserted, power operated means for effecting movement of one of said pressing members relative to the other, a wiper plate in contact with which the box end is advanced toward the pressing members and over which the box fits when the box end is inserted between the pressing members, a presser bar disposed substantially in the plane of the wiper plate and in the path of and engaged by the box end during the advance of the box along the plate to the pressing members, said presser bar being movable inwardly of the plane of the wiper plate to effect actuation of the power-operated means, and the bar likewise being displaceable in the direction of advance of the box end to the pressing members, and means for preventing inward movement of the presser bar when said bar is displaced in the direction of box advance.

3. A box making machine for securing the ends of a partially formed box, said machine comprising relatively movable pressing members between which adhesively-coated and inwardly folded portions of a box end are adapted to be inserted, power operated means for effecting movement of one of said pressing members relative to the other, a wiper plate in contact with which the box end is advanced toward the pressing members and over which the box fits when the box end is inserted between the pressing members, a presser bar disposed substantially in the plane of the wiper plate and in the path of and engaged by the box end during the advance of the box along the plate to the pressing members, said presser bar having a normal position in which it is movable inwardly of the plane of the wiper plate to effect actuation of the power-operated means, and said bar likewise having a displaced position to which it is moved by engagement with the box end as the latter advances toward the pressing members, and an abutment disposed to the rear of and aligned with the presser bar when in displaced position for preventing inward movement and actuation of the machine during advance of the box toward the pressing members.

4. A box making machine for securing the ends of a partially formed box, said machine comprising relatively movable pressing members between which adhesively-coated and inwardly folded portions of a box end are adapted to be inserted, a power operated reciprocating member for moving one of the pressing members toward and from the other pressing member, ball and socket connections between the reciprocating member and the pressing member carried thereby, and means for mounting

the other pressing member in laterally adjustable relation to the movable pressing member to vary the distribution of pressure over the box end.

5. A box making machine for securing the ends of a partially formed box, said machine having pressing members comprising a former block and a relatively movable pressure plate between which members adhesively coated and inwardly folded portions of a box end are adapted to be inserted, with the forward edge of the former block closely adjacent the inside of the box bottom, power-operated means for effecting movement of the pressure plate, a wiper plate disposed substantially in the plane of the forward edge of the former block and extending into proximity thereto, a presser bar in control of the power-operated means and mounted intermediate the wiper plate and the former block for movement inwardly when pressure is applied to the box bottom, said presser bar likewise being displaceable toward the former block in the direction of box advance, an abutment rearwardly of and aligned with the presser bar when the latter is displaced toward the former block during box advance, and connections between the presser bar and the power operated means for adjusting the presser bar relative to the edge of the former block and to the abutment to cause the presser bar to project forwardly of the plane of the wiper plate and edge of the former block and to be displaceable onto the abutment by the box end to prevent inward movement of the bar during box advance.

6. A box making machine for securing the ends of a partially formed box, said machine comprising relatively movable pressing members between which adhesively-coated and inwardly folded portions of a box are adapted to be inserted, power operated means for effecting movement of one of said members relative to the other, a presser bar adjacent one pressing member and engaged by the box in the advance of the latter to the pressing members and engaged by the interior of the box when the box end is fully inserted between the pressing members, said presser bar being movable inwardly of the adjacent pressing member to actuate the power-operated means upon the application of pressure by the operator to the box bottom in the vicinity of the presser bar, said presser bar likewise being displaceable by the box end along the path of box advance toward the pressing members, and means engageable by the bar when displaced along the path of box advance for preventing actuation of the power operated means during advance of the box to the pressing members.
